UNITED STATES PATENT OFFICE

LOUIS A. PRESTEK, OF SEATTLE, WASHINGTON

MUSICAL SIGNALING DEVICE

Application filed June 6, 1930. Serial No. 459,497.

This invention relates to improvements in signaling devices, and it consists of the constructions, combinations and arrangements herein described and claimed.

An object of the invention is to provide a signaling device the principles of which are well adapted to application to a musical horn for motor vehicles which horn is herein described as one improvement of the invention, an outstanding purpose being to enable the operator to either cause the playing of a tune or melody by pressing one button or cause the sounding of a chord by the pressing of another button.

Another object of the invention is to provide a musical horn in which the record cylinder for playing one melody is replaceable by another cylinder for playing another melody, and in which a chord, composed of a predetermined combination of notes, can be sounded irrespective of the record cylinder at the option of the operator.

Other objects and advantages will appear in the following specification, reference being had to the accompanying drawings in which

Figure 1 is a section of the improved musical horn, parts being shown in elevation.

Figure 2 is a diagram of the electrical circuit.

Figure 3 is a vertical section taken on the line 3—3 of Figure 1, parts being shown in elevation.

Figure 4 is a section of the horn duplicating a portion of Figure 1, but illustrating the action of the magnet in opening one of a plurality of valves for the sounding of a chord.

Figure 5 is a section taken on the line 5—5 of Figure 1.

Figure 6 is a section taken on the line 6—6 of Figure 1.

As already indicated above, the improved signaling device is herein described as a musical horn for motor vehicles. This use

is described only as one illustration, for in practice the signaling device will be used in connections other than automobiles.

It is a purpose to place at the disposal of the motorist a horn with which a wide choice of melodies is possible, the only limitation being the number of record cylinders of which there must be one for each desired melody. In continuation of this idea it is possible for the motorist to sound a prearranged chord irrespective of what record cylinder happens to be in place.

A base, generally denoted 1, comprises the support of a plurality of horns 2 which comprise bell-mouthed tubes 3 (Fig. 1) that are screwed into one side of an equal plurality of bosses 4 on the base 1, into the other sides of which bosses mouthpieces 5 are secured. Each has a reed 6, and a thimble 7 secured to the respective boss over the mouthpiece 5 defines an air chamber into which air is discharged in order to vibrate the reed and thus give forth a note.

Nine horns are herein used, although the number may vary in practice. The use of nine horns is preferred because of the wider range of melodies that can be played. Each reed 6 will be pitched to a different note, and it is by means of cams 8 on a record cylinder 9 (Fig. 1) that air is allowed to pass to the various air chambers and thus sound the horns in such successions or in combinations as to play the particular melody that a given cylinder 9 represents.

For this purpose the air chambers 7 of horns 2 have connection by means of ducts 10 with an air manifold 11 which, in common with a pump casing 12, is defined by a cover 13, suitably secured in front of the base 1 in an air tight manner around the contacting edges. A port 14 (Fig. 1) affords continuous communication of the pump casing 12 with the manifold 11. Air appropriately admitted to the casing 12 will be driven under pressure into the manifold 11 by the action

of blades 15 (Fig. 3) slidably carried by a rotor 16 affixed to one end of the shaft 17 to an electric motor 18.

Revolution of the rotor 16 fills the manifold 11 with air in readiness to sound the horns 2. The passage of the air to the ducts 10 is controlled by ball valves 19 that are normally seated over the entrances to the ducts by springs 20. Rods 21 are in contact (or nearly so) at the respective ends with the valves 19 and cylinder 9, so that as the latter revolves and the cams 8 move under the valve rods the valves 19 are unseated and air is liberated from the manifold 11 for passage to the various air chambers 7 in the manner already pointed out.

The valve rods 21 are supported and guided near the ends upon walls 22, 23 that form part of the base 1. It is in the wall 22 that the ducts 10 are formed. The wall 23 is actually part of a tube into which the record cylinder 9 is inserted. The record cylinder has recesses 24 at one end for the reception of a turning fork 25, and at the other end has a pintle 26 which is engageable in the central hub 27 of a closure cap 28 for the tube 23. The record cylinder is thus afforded an adequate bearing.

Meshing gears 29, 30, by the last of which the fork 25 is carried, are adapted to be driven by the motor 18 as long as a movable clutch member 31 is held in engagement with a complementary clutch member 32 by means of a spring 33. The clutch member 31 is splined to the shaft 17 at 34 (Fig. 6). The clutch member 32 is perfectly loose on the shaft 17. It includes a worm pinion 35 which meshes with a worm gear 36 (Fig. 6) on the suitably supported shaft 37 of the gear 29.

Thus it will be seen that when the motor 18 is operated, the turning of its shaft 17 is imparted to the record cylinder 9 (Fig. 1) by way of the clutch members 31, 32, worm pinion and gears 35, 36 and gears 29, 30, thus causing the playing of the melody for which the cams 8 are set. The motor 18 is embraced by a circuit which is as follows:

One terminal of a battery 38 is connected with one brush of the motor by means of wires 39, 40, the other terminal of the battery being connected by means of a wire 41 with an automatic control disc 42 which is fixed to the shaft 43 in common with the gear 30. This disc has a cut-out spot 44 composed of an insert of insulation. Brushes 45, 46 bear on the periphery of the disc 42, these being connected by wires 47, 48 with the opposite sides of a push button switch 49.

A wire 50 from the other brush of the motor 18 has a branch connection 51 with the wire 48. Upon wishing to play a melody the operator has only to give the button 49 a momentary push, then release it whereupon the action will be as follows:—Current primarily flows from battery 38 over wires 39, 40 to

motor 18, over wires 50, 51, 48 to the button 49, thence over wire 47, brush 45, disc 42 and wire 41 to the battery. As soon as the disc 42 has turned far enough to displace the cut-out spot 44 from the brush 46, current secondarily flows from battery 38 over wires 39, 40 to motor 18, wires 50, 51 and 48 to brush 46, through disc 42 and over wire 41 to the battery. This secondary current flow continues until the cut-out spot 44 reaches the brush 46, whereupon the secondary current is opened and the motor 18 caused to stop.

A selection of horns 2 is preliminarily made for the sounding of a chord. Corresponding rods 21 are selected, and each of the selected ones is fitted with a stop 52 (Fig. 5) against which the forked end of a lever 53 can push. There is a plurality of these levers 53 (Fig. 1) attached to a cross shaft 54. An armature 55 on the cross shaft confronts the pole piece of an electro-magnet 56 which, when energized, attracts the armature and simultaneously disengages the clutch member 31 and shifts the selected rods 21 so as to unseat the corresponding valves 19 and sound the chord which they represent. For the first purpose the cross shaft 54 has a clutch fork 57 in engagement with the member 31.

The manner in which the magnet 56 is energized and the record cylinder 9 cut out is as follows:—A push button switch 58 (Fig. 2) has one contact with which an extension of the wire 50 is connected, a second contact with which a wire 59 is connected and a third contact with which a wire 60 from one terminal to the magnet 56 is connected. The other terminal of the magnet is connected with an extension 61 of the wire 39. Upon pressing the button 58 current will flow from battery 38 over wires 39, 60 to magnet 56, wire 60, switch 58 and wires 59, 47 to brush 45, returning to battery by way of disc 42 and wire 41. This actuates the selected rod 21 as already explained.

But it is also necessary for the motor 18 to be energized in order that the pump blades 15 may supply the air for the blowing of the selected trumpets 2. This is accomplished as follows:—There is a division of the current from battery 38 over wire 39 at the wire 40, which current flows through motor 18, over wire 50 to switch 58, wires 59, 47 to brush 45, returning to battery by way of disc 42 and wire 41.

Since in the sounding of the chord the record cylinder 9 is cut out by the unclutching of the complementary member 32 it follows that the automatic function of the control disc 42 is suspended. The sounding of the chord will, therefore, continue as long as the operator applies pressure to the button 58 (Fig. 2). But in the instance of the button 49, as has been brought out already, it is nec-

essary to apply momentary pressure only whereupon the start given the disc 42 will continue the turning of the record cylinder 9 until one revolution has been completed, 5 whereupon the turning will be stopped automatically when the cut-out stop 44 reaches the brush 46.

It will be further understood that the pump 15, 16 operates with the depression of each 10 button 49, 58. This is necessary in order to supply the air for the operation of the horns. The choice of a chord is a matter of the initial setting of the levers 53 (Fig. 1). Ordinarily this setting will be made at the factory. The record tube 23 is accessible to the 15 motorist for the purpose of replacing the record cylinder 9.

The choice of a variety of melodies may be 20 played by having as many different record cylinders on hand. The melody of an automobile horn capable of playing a variety of melodies will appeal to a large portion of the motoring public, and the replacement by a 25 melodious tune for the raucous sounds customarily projected at pedestrians is calculated to inspire in the latter more respect for the warning intended to be issued.

While the construction and arrangement of the improved musical signaling device is that 30 of a generally preferred form, obviously modifications and changes may be made without departing from the spirit of the invention or the scope of the claims.

I claim:—

35 1. A signaling device comprising a plurality of sound-making elements, actuatable means to cause the sounding of the elements, a record for operating the actuatable means and playing a selected melody, and means having a fixed setting for operating a pre-arranged set of the actuatable means irrespec- 40 tive of the record.

45 2. A signaling device comprising a plurality of horns, a source of air to blow the horns, valve means to control the passage of air to the respective horns, a record having means to displace the valve means in successions and combinations for the playing of a melody, and means to displace predetermined 50 ones of the valve means irrespective of the record to sound a chord.

55 3. A signaling device comprising a plurality of horns, a pump to supply air for the blowing of the horns said pump having driving means for operating it, valve means to control the flow of air to the respective trumpets, a record in driving connection with said driving means for actuating the valve means simultaneously with the pump for the 60 playing of a melody, and means for simultaneously disconnecting the record from the driving means and actuating predetermined ones of the valve means irrespective of the record for the sounding of a chord.

65 4. A signaling device comprising a plu-

rality of sound-making elements, individual means for actuating the respective elements, an exchangeable record for operating upon said individual means according to a choice of records thus to enable playing a selected melody, and means to simultaneously render the record inoperative and actuate a predetermined group of the elements to sound a chord.

5. A signaling device comprising a plurality of horns, means to supply air for the sounding of the horns, individual valve means for controlling the flow of air to the respective horns, a revoluble record, rods interposed between the valve means and the record for the variegated displacement of the valve means and the playing of a melody, and means for simultaneously stopping the record and actuating predetermined ones of the rods for the regular displacement of the respective valve means and the playing of a chord.

6. A signaling device comprising a plurality of horns, a pump for supplying air to the horns, said pump having a drive means, valve means for controlling the flow of air to the horns, rods to actuate the valve means, a record for operating on the rods causing the playing of a melody, means driven by the valve means for revolving the record, the driven means including a clutch for connecting the driven means with the drive means, and means for simultaneously disengaging the clutch to stop the record and actuate a predetermined number of the rods for the playing of a melody.

7. A signaling device comprising a plurality of sound-making elements, means to control the application of operating energy to the respective elements, a record for actuating the control means successively thus to play a melody, group-operating means for actuating a group of the control means to play a chord, electrical means including a source of energy and motor with driving connection to the record and said energy producing means, and a circuit having a switch adapted to be momentarily closed and having automatic control means for substantially keeping the circuit closed a fixed length of time and a second circuit including a magnet and said motor, being adapted for closure to actuate the group-operating means to disconnect the driving connections of the record and cause a group operation of said control means.

8. A signaling device comprising a plurality of horns, an electric motor and a pump operable thereby to supply the horns with air, valve means to control the flow of air to the respective horns, separately controlled electrical circuits embracing the motor, one of said circuits including an electro-magnet, a record having driving connections operable by the motor in common with the pump upon closure of one of the circuits for actuating the valve means to play a melody, and group-

actuating means operable by the electro-magnet in common with the motor upon closure of the other circuit having means to disconnect the record and to displace a group of the **5** valve means for the playing of a chord.

9. A signaling device comprising a plurality of sound-making elements, individual means for actuating the respective elements, a record for operating upon said individual **10** means to enable playing a selected melody, and means to simultaneously render the record inoperative and actuate a predetermined group of the elements irrespective of the record.
